WALL CONSTRUCTION AND SECURING
MEANS THEREFOR

George Miller Thomson, Caledonia, Ontario, Canada, assignor to Gypsum, Lime, and Alabastine, Canada, Limited, Paris, Ontario, Canada

Application March 10, 1930. Serial No. 434,788

2 Claims. (Cl. 72—118)

This invention relates to the securing of wall board to a support such as the wooden studding of a building, and is more particularly applicable to the securing of wall board of the type consisting of a paper-covered core of cementitious material, such as gypsum.

It is customary to hold such boards in place by means of nails having a cylindrical shank, pointed at one end and provided with a thin, circular, flat head at the other end, the shank being formed, throughout the whole or a major portion of its length with projecting ribs intended to cause the nail to be anchored more firmly in the studding or other support.

15. This method of securing wall boards has several disadvantages which are obviated by the present invention, according to which the boards are secured in position on the support by means of an improved nail having a tapering or conical head and barbs or serrations directed backwardly towards the head. The barbs or serrations are preferably confined to that portion of the shank which is adapted to enter the wooden or other support.

25. The advantages of the present invention as compared with customary practice will be described hereinafter.

The invention consists in the features, construction and arrangement of parts hereinafter described and more particularly pointed out in the appended claims.

Referring now to the accompanying drawing, which illustrates, by way of example, one convenient embodiment of the invention,

35. Figure 1 is a sectional view showing the form of nail ordinarily employed for the purpose described;

Figure 2 is a similar view illustrating the use of the improved nail;

40. Figure 3 is a section on line 3—3 of Figure 2;

Figure 4 is a view similar to Figure 3, showing a modified arrangement of barbs, and

Figure 5 is a fragmentary sectional elevation illustrating a modified form of nail head.

45. The numeral 1 indicates the paper liners and 2 the cementitious core of the wall board or lath, while the wooden studding or other support is indicated at 3.

The ordinary form of nail, shown in Figure 1, 50. comprises a cylindrical shank 4, pointed at the end 5 and formed with a thin, flat, circular head 6 at the other end. The shank is also formed with two series of projecting ribs 7 extending partially round the shank. When a nail of this type is hammered through the wall board and

into the support 3 it is impossible to have the outer surface of the head 6 flush with the outer surface of the wall board without tearing the outer paper liner at 8. This tearing causes a paper disc 9 to be detached and pressed into the core 2, and the portion of the core under the head is compressed and crushed. The edge of the paper adjacent the circular line 8 is thus not held by the nail-head 6 and may rise up from the core 2 and present an untidy appearance.

Moreover, the reaction of the compressed board to the force applied thereto by the head 6 is in a direction parallel to the axis of the shank 4 (see arrows 10), and any vibration or bending of the wall at the unsupported points between 70

the studding is liable to cause the nail to be withdrawn from the support 3 so that the board is no longer securely held in place on the supports.

According to the present invention (see Figure 2) the nail comprises a shank 11, which is preferably substantially cylindrical, and is provided with the usual pointed end 12. The head 13, however, is of considerable thickness and tapers from the outer surface of the head, where it has minimum thickness, to the shank, being preferably in the form of a truncated cone having its conical surface arranged at an angle of approximately 45° with respect to the outer surface 14 of the head. This arrangement possesses at least 75

two important advantages.

Firstly, the nail can be driven in until the surface 14 is flush with the outer surface of the wall without tearing the paper 1 in the objectionable manner illustrated in Figure 1. The point 12 perforates the paper at 15, and the paper immediately surrounding the perforation is clamped tightly between the head 13 and the core 2, thus ensuring that the outer paper liner 1 cannot break away from the core 2.

Secondly, the reaction of the board on the head 95 is in the direction of the arrows 16, which is clearly less favourable to the withdrawal of the nail than the reaction forces indicated by the arrows 10 in Figure 1.

Moreover, the portion of the core affected is 100 displaced in a lateral direction rather than vertically, thus permitting the accommodation of the displaced portion without alteration of the exposed surfaces of the board. The invention therefore enables the board to resist more strongly any tendency of the nails to be withdrawn by vibration or bending of the board.

In place of the ribs 7, the barbs or serrations 17 are provided on the shank 11. These barbs 110 may be arranged in two series, partially sur-

rounding the shank as indicated in Figures 2 and 3, or may be disposed in three series as illustrated in Figure 4. Each barb may extend completely around the shank, if desired, or any other arrangement may be adopted, to ensure that at least some of the barbs will always be favourably disposed for engagement under the unbroken parts of the fibre of the wood when the nail is driven into the support 3.

10 It will be seen that the upper ribs 7, shown in Figure 1, do not perform any useful function, and according to the present invention the barbs 17 are confined to that portion of the nail which engages the support 3. Preferably the cylindrical portion immediately adjacent the pointed end 12 is devoid of barbs so that the nail may be accurately directed into the support 3 before any barbs come into engagement with the support. Thus owing to the evenly tapered or 20 pointed end and the absence of barbs or serrations adjacent this portion of the nail, the tendency for the nail to be accidentally driven into the wall at an angle other than a right angle is largely overcome.

25 While the under surface of the head 13 is preferably conical, this shape is not essential. The surface must taper gradually but not necessarily uniformly. For example, it might be concave, as indicated in Figure 5. The term 30 "conical" as employed in the claims is intended

to include any such gradually tapering formation.

I claim:

1. In combination, a wall board of the kind comprising a cementitious core and paper liners adhering to said core; a support; a nail shank anchored in said support and a tapered head integral with said shank, a portion of the outer paper liner being clamped between the tapered surface of said head and said core, and said head having a flat, outer surface in a plane at right angles to said shank substantially flush with the outer face of the wall board and meeting said tapered surface at a sharp, circular edge. 80

2. In combination, a wall board of the kind comprising a cementitious core and paper liners adhering to said core; a support; a nail shank anchored in said support and a conical head integral with said shank, a portion of the outer paper liner being clamped between the conical surface of said head and said core, and said head having a flat, outer surface of large diameter in relation to the diameter of the shank and the conical surface of the head being arranged 95 at an angle of substantially 45° with respect to the shank and terminating at its larger end in a sharp, circular edge. 100
